UNITED STATES PATENT OFFICE.

EDGAR W. ROBINSON, OF INDIANAPOLIS, INDIANA.

DESIGN FOR A WATER-HEATER.

SPECIFICATION forming part of Design No. 30,801, dated May 16, 1899.

Application filed February 25, 1899. Serial No. 706,883. Term of patent 3½ years.

To all whom it may concern:

Be it known that I, EDGAR W. ROBINSON, a citizen of the United States, residing at Indianapolis, in the county of Marion and State 5 of Indiana, have invented and produced a new and original Design for Water-Heaters Adapted to be Attached to a Stove for the Purpose of Heating Water for Domestic Use; and I do hereby declare the following to be a full, clear, 10 and exact description of the invention.

The object of my invention is to procure a novel form or design known as a "water-heater" with this and other objects in view, which will hereinafter be more fully described and specifically set forth in the appended claim.

In the accompanying drawings, Figure 1 is a top view showing a series of hollow tubes that are cast in an inner circle. Fig. 2 shows 20 a side elevation with connections top and bottom.

The novel features of my design consist in the main cylinder A, which is oval in form, as shown in Fig. 1, and has an opening a, with a rim or flange a' surrounding and projecting from the same. Appearing within the opening a are a series of tubes b b b, while at top and bottom of the main cylinder are openings b' b', leading to the interior of the same. 25

Having thus fully described my invention, 30 what I claim as new and useful, and desire to secure by Letters Patent, is—

The design for a water-heater, substantially as herein shown and described.

In testimony whereof I affix my signature, 35 in presence of two witnesses, this 15th day of February, 1899.

EDGAR W. ROBINSON.
